(57) **CLAIM**

The ornamental design for a portable insulin auto-syringe, as shown and described.

DESCRIPTION

FIG. 1 is a perspective view of a portable insulin auto-syringe according to the present design;

FIG. 2 is a front view of the design as shown in FIG. 1;

FIG. 3 is a rear view of the design as shown in FIG. 1;

FIG. 4 is a left side view of the design as shown in FIG. 1;

FIG. 5 is a right side view of the design as shown in FIG. 1;

FIG. 6 is a top plan view of the design as shown in FIG. 1; and,

FIG. 7 is a bottom plan view of the design as shown in FIG. 1.

The article is made of metal, synthetic resin and glass.

The article is possible being carried by the user.

The article is possible being automatically inject insulin into the body by sticking a needle connected with a syringe unit onto the skin.
